US00D771569S

(12) **United States Design Patent** (10) **Patent No.:** **US D771,569 S**
Smith (45) **Date of Patent:** **** Nov. 15, 2016**

(54) **ELECTRICAL CONNECTOR WITH CABLE ARMOR STOP**

(71) Applicant: **Bridgeport Fittings, Inc.**, Stratford, CT (US)

(72) Inventor: **Lawrence J. Smith**, Stamford, CT (US)

(73) Assignee: **BRIDGEPORT FITTINGS, INC.**, Stratford, CT (US)

(**) Term: **15 Years**

(21) Appl. No.: **29/554,623**

(22) Filed: **Feb. 12, 2016**

(51) **LOC (10) Cl.** **13-03**

(52) **U.S. Cl.**

USPC **D13/151**

(57) **CLAIM**

The ornamental design for an electrical connector with cable armor stop, as shown and described.

DESCRIPTION

FIG. 1 is a front perspective view of an electrical connector with cable armor stop showing my new design.

FIG. 2 is a right side view thereof.

FIG. 3 is a left side view thereof.

FIG. 4 is a front view thereof.

FIG. 5 is a rear view thereof.

FIG. 6 is a top view thereof; and,

FIG. 7 is a bottom view thereof.

1 Claim, 2 Drawing Sheets
